United States Patent Office

Des. 206,805
Patented Jan. 31, 1967

206,805

BATTERY CHARGER

Richard A. Cunitz, Birmingham, Mich., assignor to AMT Corporation, Troy, Mich., a corporation of Michigan

Filed July 2, 1965, Ser. No. 86,008

Term of patent 14 years

(Cl. D26—15)

FIG. 1

FIG. 2

FIG. 1 is a perspective view of a battery charger embodying my novel design.

FIG. 2 is a side elevational view of the same, the other side being substantially identical.

I claim:

The ornamental design for a battery charger, as shown and described.
